UNITED STATES PATENT OFFICE.

GUSTAVE F. MORANZ, OF CHICAGO, ILLINOIS, ASSIGNOR TO CHICAGO VARNISH COMPANY, OF CHICAGO, ILLINOIS, A CORPORATION.

DRY-KILN.

1,103,608.

Specification of Letters Patent. Patented July 14, 1914.

Application filed April 16, 1913. Serial No. 761,544.

To all whom it may concern:

Be it known that I, GUSTAVE F. MORANZ, a citizen of the United States, and a resident of the city of Chicago, county of Cook, and 5 State of Illinois, have invented certain new and useful Improvements in Dry-Kilns, of which I do declare the following to be a full, clear, and exact description, reference being had to the accompanying drawings, forming 10 part of this specification.

My present invention has for its object to provide an improved dry kiln which, while adapted for a great variety of uses, is especially well suited for the drying of 15 articles such as piano cases, carriages, or the like, that have been painted and varnished and which require to be very carefully and uniformly dried.

The invention consists in features of novelty hereinafter described, illustrated in the accompanying drawings and particularly pointed out in the claims at the end of this specification.

Figure 1 is a view in vertical section 25 through a dry kiln embodying my invention, this view being taken on line 1—1 of Fig. 3. Fig. 2 is a plan view of dry kiln embodying my invention, parts being shown in horizontal section. Fig. 3 is a view in vertical 30 section in line 3—3 of Fig. 1. Fig. 4 is a view in vertical section on line 4—4 of Fig. 1.

My improved dry kiln is shown as comprising a drying room or chamber 10, having double walls 11 and 12, the inner wall 12 being preferably faced or covered with sheets of metal 13. One of the vertical walls of my improved kiln will be furnished with suitable doors 14, and the roof 15 of the kiln 35 is also shown as formed of inner and outer walls 11 and 12, the inner wall being lined with sheet metal 13. The inner and outer vertical walls of the body of the kiln will be spaced apart by suitable studding 16 and 40 the walls of the roof will also be spaced apart by strips 17, as shown. Between the studding 16 of the vertical walls, adjacent the bottoms of the walls, extend the strips or plates 18, these plates being spaced a 45 slight distance above the floor of the kiln (preferably about two inches) so as to form inlet openings 20 that extend substantially from end to end of the kiln (see Figs. 1 and 4).

55 The floor of my improved kiln is shown

as arranged in line with the floor 22 of the adjoining room of the building wherein the kiln is located, or upon a level with the surface from which the material will be introduced in to the kiln. My improved 60 floor is formed of removable sections, three of such sections being shown in the accompanying drawing. Each of these floor sections consists of two layers, preferably of wood, the upper and under layers being 65 formed of strips of different widths and so spaced apart that the continuity of the air currents through the double floor will be broken. Preferably the under layer of the floor consists of wooden strips 25, say three 70 inches in width, and spaced say two inches apart, to form openings between the strips, while the upper layer of flooring consists of narrower strips 27 (say 2½ inches wide) set more closely together to form the narrow 75 spaces 28 between such strips. The spaces 26 between the strips 25 of the under layer of the flooring are arranged beneath the strips 27 of the upper layer of the flooring, so that as the heated air passes upward 80 through the flooring, continuity of the air currents will be broken and a very uniform distribution of the air throughout the entire body of the kiln will be effected. The upper and lower layers of the flooring will be 85 spaced apart by longitudinal strips 29 to which the upper and lower strips 27 and 25 will be fastened.

Beneath the flooring of the kiln extend the joists or stringers 30, whereon the flooring is removably supported. These joists or stringers 30 are set at convenient distances apart and at their ends extend the transverse joists 31.

Beneath the inner walls 12 of the ends of the kiln extend the strips 34 from which depend the baffle-plates 35 that extend between the joists 30, and these baffle-plates form, with the joists 31, the air conduit 36, whereby air will pass from the air-inlet 100 openings 20.

Between the joists or stringers 30 are arranged the heating pipes 40 that will be connected to suitable supply pipes or headers, in a manner well understood by those familiar with this class of structures. In the roof of the kiln are formed a plurality of air-discharge passages 45 that extend approximately from end to end of the kiln. These air-discharge passages are narrow 110

slots arranged at such distance apart and in such number as to insure a uniform discharge of the heated air from the different parts of the kiln.

- 5 Both the air-inlets 20 and the air-outlets 45 are provided with improved construction of valves whereby the passage of air therethrough can be most conveniently and accurately regulated. The valve for each of the 10 air-inlet passages consists of a long plate 50 that is pivotally connected to hanger-links 51, the upper ends of which are pivotally attached, as at 52, to the side wall of the kiln. These hanger-links 51 give to the 15 valve-plate 50 a parallel ruler movement and while allowing the valve-plate to be readily shifted to open or close the air-inlet 20, insures an accurate opening and closing of the air-inlet throughout its entire length.
- 20 In order to hold the valve-plate 50 at any desired position, one of the links 51 (see Fig. 4) is provided with a series of notches 53 adapted to be engaged by a dog or pawl 54 that is pivoted, as at 55, upon a standard 25 56. It will be readily understood that by shifting the position of the dog or pawl 54, the valve-plate 50 may be held at any desired elevation.

The air-outlets 45 in the roof of the kiln 30 are provided each with a valve-plate 50^a, similar in construction to the valve-plate 50 just described. Each of these valve-plates 50^a is pivotally connected to links 51^a, the outer ends of which are pivoted, as at 52^a, 35 to the roof. By preference, the end of each of the valve-plates 50^a is provided with a bent or upturned portion 58, to permit the valve-plate 50^a to be conveniently shifted, but inasmuch as each valve-plate 50^a rests 40 upon the roof, it is not necessary to provide any device for holding the valve-plate 50^a in adjusted position.

From the foregoing description, it will be seen that when the valve-plates 50 and 50^a 45 have been adjusted so as to open the inlets 20 and outlets 45 of the kiln to the required extent, air will pass through the inlets 20 and down the passageways 36 below the baffle-plates 35 and into the spaces between the 50 joists or stringers 30 and beneath the floor. Here the air will be heated by the steam 55 pipes 40, and thus heated, will rise through the spaces 26 and 28 formed in the floor of the kiln. The spaces 26 and 28 between the slats comprising the upper and lower layers of the floor being out of alinement, a most thorough and uniform-admission of the heated air into the body of the kiln will be secured. By means of the plurality of long, 60 narrow air-outlets in the roof of the kiln, and because of the accurate regulation of the discharge of air through these outlets, I have found in practice that a most uniform heating of the body of air within the 65 kiln can be secured. This feature is par-

ticularly advantageous in a kiln especially designed for the drying of piano cases, carriage bodies, or similar painted and varnished work which needs to be subjected to uniform heat without exposure to excessive 70 drafts or currents of air.

I prefer that my improved flooring should be made in removable sections, as by this means ready access can be had to the piping beneath the floor.

While I have described what I regard as the preferred embodiment of my invention, it will be readily understood that the precise details of the invention may be varied without departure from the scope thereof, 80 and that features of the invention may be employed without adoption as an entirety.

Having thus described my invention, what I claim as new and desire to secure by Letters Patent, is:—

1. A dry kiln comprising a drying chamber having air inlets and outlets at its bottom and top, heating pipes adjacent the bottom of said chamber and a floor in the lower part of said chamber and above said heating pipes, said floor forming a support for the objects to be dried and having upper and lower layers each formed of strips spaced apart, the spaces between the strips of the upper layer being arranged out of line with the spaces between the strips of the lower layer.

2. A dry kiln comprising a drying chamber having air inlets and outlets at its bottom and top, heating pipes adjacent the bottom of said chamber and a floor in the lower part of said chamber and above said heating pipes, said floor being formed of removable sections having upper and lower layers separated from each other and each formed of strips spaced apart, the spaces between the strips of the upper layer being arranged out of line with the spaces between the strips of the lower layer.

3. A dry kiln comprising a drying chamber having air inlets and outlets at its bottom and top, heating pipes adjacent the bottom of said chamber and a floor in the lower part of said chamber and above said heating pipes, said floor being formed of upper and lower layers separated from each other and each formed of strips spaced apart, the strips of the upper layer being materially narrower and closer together than the strips of the lower layer and the spaces between the strips of the upper layer being arranged out of line with the spaces between the strips of the lower layer.

4. A dry kiln comprising a drying chamber having air inlet and outlet passages at its bottom and top and a valve for the air-inlet passage consisting of a vertically movable plate and links for suspending said plate adjacent the air-inlet passage.

5. A dry kiln comprising a drying cham-

ber having air inlet and outlet passages at its bottom and top, a valve for the air-inlet passage consisting of a vertically movable plate, links for suspending said plate adja-

cent the air-inlet passage and a dog or pawl for adjustably holding said plate in different positions.

6. A dry kiln comprising a drying chamber having air inlet passages extending 10 through the outer walls of the kiln approximately from end to end of the kiln at opposite sides thereof adjacent its bottom and having a plurality of outlet passages extending through the roof and approximately 15 from end to end thereof, and adjustable sliding plates for regulating the flow of air passing through said inlet and outlet passages.

7. A dry kiln comprising a drying chamber having air inlet passages leading 20 through the outer walls adjacent the floor of said chamber, heating pipes located beneath the floor of said chamber, and baffle

plates arranged between said inlet passages and said heating pipes and extending to a 25 point below said heating pipes to direct the air beneath said pipes.

8. A dry kiln comprising a drying chamber having air inlet passages leading through the outer walls adjacent the floor 30 of said chamber, a floor in the lower part of said chamber and having spaces there-through for the passage of air, a series of stringers extending from end to end of said dry kiln beneath the floor thereof and at right 35 angles to the walls wherein the air inlet pas-sages are formed, heating pipes arranged between said stringers and beneath said floor, and deflector plates extending trans-versely of said stringers and leading from 40 said air inlet passages to points below said heating pipes.
